METHOD AND APPARATUS FOR LOADING
ARTICLESHenry B. Koonce, High Point, N. C., assignor to
Atlantic States Motor Lines, Inc.

Application February 16, 1939, Serial No. 256,809

29 Claims. (Cl. 214—152)

This invention relates to a method of an apparatus for stacking, loading and transporting heavy cylindrical articles and more particularly to spool-shaped articles such as spools or beams for cordage which may be thread and the like.

The present invention relates more specifically to the stacking, loading, transportation and hauling of large and heavy spools or beams of commercial thread materials so that the same may be handled in an expeditious manner and minimize any danger of damage during transportation. When spools of rayon thread, for example, are transported by trucks over long distances, considerable care is necessary in properly bracing the cargo and considerable difficulty has frequently been experienced with methods heretofore employed, by the load shifting in the container or truck body with a resulting costly damage to the thread on the spools as well as to the truck body. This is especially true when these heavy spools are placed in tiers or superimposed rows, and serious accidents have resulted due to sudden stops of the truck for unavoidable reasons. It will be remembered that these individual spools or beams of thread as they are sometimes called, frequently weigh a thousand pounds or more, and therefore it is necessary that they be loaded and anchored in the container or vehicle body in which they are being transported in a positive and reliable manner.

The present methods and apparatus heretofore employed in loading and stacking these spools of thread have been defective in properly preventing the accidental shifting of the rows of spools on the vehicle floor or the individual spools of a row.

One important object of the present invention is to provide a novel method of and apparatus for arranging cylindrical articles on the floor of a freight container such as a freight car or motor truck body so as to reduce to a minimum any danger of the load shifting during transportation.

Another object of the invention is to provide a novel form of apparatus for supporting and anchoring individual spools of thread together as well as anchoring the spools to the floor or sides of the container or truck body.

Another object of the invention is to provide an apparatus of the character designated which shall reduce to a minimum special apparatus for stacking freight material of this kind and which may also be readily dismantled and stored in a minimum space to provide for loading other types of freight.

Another object of the invention is to provide

an apparatus of the character designated in which the individual spools shall be anchored relative to each other in separate row units and anchoring the units relative to the floor of the container as well as provide for accidental shifting of the units relative to each other under extreme conditions of transportation or hauling.

A further object of the invention is to provide an apparatus of the character designated which shall be inexpensive and simple in construction and positive in operation to prevent any shifting of the articles relative to each other as well as relative to the floor and walls of the container in which they are stacked.

These and other objects of the invention will be more apparent from the accompanying specification and drawings and more particularly set forth in the claims.

In the drawings—

Fig. 1 is a vertical sectional view showing of apparatus constructed and arranged in accordance with the present invention.

Fig. 2 is a plan view of the apparatus shown in Fig. 1.

Fig. 3 is a fragmentary plan view of a platform for supporting a superimposed row of spool-shaped articles.

Fig. 4 is a sectional view on line 4—4 of Fig. 1.

Fig. 5 is a fragmentary sectional view of guide members shown in Fig. 1; and

Fig. 6 is a fragmentary sectional view on line 6—6 of Fig. 5.

Referring to Figs. 1 and 2 of the drawings, there is shown a preferred embodiment of the invention in which a plurality of cylindrical articles such as heavy spools of thread indicated by the numeral 10 are loaded and stacked on the floor 11 of a conventional form of truck body indicated generally by dotted lines 12. The truck floor is supported on a conventional type of angle iron frame members indicated by the numeral 13.

The individual spools of thread loaded and stacked in accordance with the present invention are of the conventional type having end flange head members 14 and 15 and an integral axle 16 which projects beyond the head members as indicated. These heavy spools are sometimes called beams of thread in the textile art. The spools are loaded by placing a desired number of spools on the floor in aligned position and securing them in spaced relation by a pair of separate side plate members 17—18 which extend adjacent to the heads of the spools in a row. These side plate members 17—18 are provided with a plurality of spaced apertures 19 which

are a little larger than the axle members 16 of the individual spools. The spacing of these apertures is substantially the width of the conventional spool heads 14-15 so that the axles of the spools engaging the apertures of the plates, hold the individual spools of a row in fixed spaced relation. These plate spacer members are placed on opposite sides of the spools and are carried by the spool axles 16 to hold the individual spools in spaced relation.

After the spools are thus spaced in alignment by the plate members, the plates 17-18 are rigidly clamped to the spool heads at several places along the row by angle iron plate members 19 and 20 and upper and lower tie rods indicated by the numerals 21 and 22 as shown in Fig. 4. These individual tie rods are threaded at their ends as indicated by the numerals 23 and 24 so as to receive nut members 25 and 26 respectively. It will thus be noted that by clamping the side plates 17 and 18 by the adjustable tie rods 21-22, the spools are held in rigid spaced relation as a row unit and all danger of any of the spools contacting each other so as to damage the thread is positively prevented in a most effective manner.

After this first unitary row of spools is placed on the truck body floor and secured by the side members 17-18 as above described, this unit is further anchored to the floor 11 by suitably placed anchored rods 27 and 28. One end of the anchor rod 27, for example, is attached to the side spool spacer members 17 by a plate member 29, and the other end of the rod is attached to the floor frame by an eye bolt 30. As indicated in the drawings the brace 28 is toward the rear of a unit and the brace 27 is at the forward end of the unit, each brace being inclined in the opposite direction to give the desired bracing and anchoring effect. Each of these anchor members is provided with a conventional form of turn buckle 31 which is adjustable to vary the tension and firmly anchor the unit. After the unit is thus anchored against longitudinal movement, it is further braced against lateral movement by means of a plurality of spacer blocks 20' which engage the side walls of the truck and the head of a spool.

From the foregoing it will be noted that the individual spools of the first row are anchored in spaced relation relative to each other to form a rigid unit and the unit is then anchored to the floor of the container thereby affording a maximum bracing effect for the individual spools and the row as a unit. This novel form of bracing eliminates the use of tracks and other forms of chocking which have been used heretofore for bracing loads of this kind.

A second or superimposed row of spools may now be stacked on the lower row if desired. This is accomplished by providing a platform 33 as indicated in Fig. 3. This platform rests directly on the spool flanges of the lower row and is of ample width to receive the flanges of the spools of the row to be formed thereon as indicated. The spools of this superimposed row are now placed on the platform and anchored in spaced relation by the same type of spacing and clamping members as heretofore described with reference to the first row. In this case a pair of side members 34 and 35 with the same type of spaced apertures for securing the spool axles and the same type of tie-rod clamp members are employed as heretofore described. This second row unit of spools is now anchored to the floor by means of anchor members 36-37. These anchor

members are of the type heretofore described and are positioned at the front and rear of the row and extend in opposite directions to provide the desired and necessary anchoring function.

5 To further provide against any movement of the individual spools or the spool unit relative to the lower unit or the container floor, the platform is separately anchored to the floor of the vehicle by a pair of anchor rods 38-39 as indicated. To further aid in retaining the platform so that it shall be held against displacement in any direction, upper and lower guide plates 40 and 41 are adjustably mounted on the platform as indicated in Fig. 3. The top engages the end 15 flange of the upper spool and the lower plate 41 engages the flange of the lower spool as shown in Figs. 5 and 6. It will thus be noted that these plates provide against any lateral shifting of the platform relative to the lower row of spools and 20 also prevents shifting of the spool row unit on top of the platform.

The plates 40 and 41 are each adjustably mounted on the platform 33 by a bolt 42 and a slot 43 provided in the side bearing portion of 25 each plate. These angle plates 40 and 41 are adjustably mounted on upper and lower cross plate members 44 and 45 forming an integral part of the platform. These cross plates 44 and 45 also serve as reinforcing members for the 30 platform.

To facilitate handling the platform it is preferably made in sections indicated by the numerals 46 and 47 and these sections may be coupled together in any suitable manner as by the hook 49 35 on eye 50.

In view of the foregoing it will be particularly noted that in the present novel construction, the individual spools of each row are rigidly secured against movement relative to each other so as to 40 eliminate any possible contact which may damage the thread on the spool and also prevents any movement relative to the floor of the container, either longitudinally or laterally.

I claim:

45 1. Apparatus for supporting and securing cylindrical-shaped articles comprising in combination, a floor support for receiving a plurality of articles rolled thereon in a row, a frame supported by the row and including side members 50 extending longitudinally of the row and engaging the opposite ends of the articles above the floor support, said frame members including means for securing the individual articles to each other in spaced relation on the floor, and 55 means for anchoring the frame to the floor.

2. Apparatus of the character designated in claim 1 including means for clamping the side frame members against the head of each article to form a rigid row unit, and means for tensioning the anchor means.

60 3. Apparatus of the character designated in claim 1 including means for cross connecting the side members to clamp the members to the articles so as to secure the articles in rigid spaced 65 relation to form a row unit, a pair of members connecting one of the clamping members and the floor for anchoring the article row unit to the floor to prevent endwise movement thereof, and other means on the floor for engaging certain 70 individual articles of the unit for preventing lateral movement of said unit.

4. Apparatus of the character designated in claim 1 in which the frame members shall extend the length of the row and be carried by the respective opposite heads of each article, means

for clamping the side members together to rigidly embrace the article heads, and brace members extending in opposite directions between the article frame clamping means and the floor to brace the row against endwise movement on the floor.

5. Apparatus for stacking and loading spool-shaped articles on a base support for transportation comprising in combination, a plurality of spools placed in a row, means for clamping the individual spools of a row to each other as a unit, a platform resting on the row of spools, and means for anchoring the platform to the spools and the base support to prevent movement in any direction.

6. Apparatus for stacking and loading spool-shaped articles on a base support for transportation comprising in combination, a plurality of spools placed in a row, means for clamping the individual spools of a row to each other as a unit, a platform resting on the row of spools, means for anchoring the platform to the base support to prevent movement in a longitudinal direction, and guide means on the platform for engaging certain of said spool ends for anchoring the platform in a lateral direction relative to the supporting row of spools and the base support.

7. Apparatus of the character designated in claim 5 in which the platform rests on the row of spools for receiving a top row of spools placed on said platform, means for guiding the platform relative to the lower row of spools, and means for clamping the spools in the top row to the platform.

8. Apparatus of the character designated in claim 5 including guide means on the under side of the platform for positioning said platform relative to the top edges of the spools in the lower row, and guide means on the upper side of the platform for aligning the spool flanges of a top row of spools on the platform.

9. Apparatus of the character designated in claim 5 including guide means on the under side of the platform for positioning said platform relative to the top edges of the spools in the lower row, guide means on the upper side of the platform for aligning the spool flanges of a top row of spools on the platform, and a unitary connection between the upper and lower guide means for aligning the flanges of the spools in the upper and lower rows for preventing relative lateral displacement thereof relative to the base support.

10. Apparatus of the character designated in claim 5 including guide means on the under side of the platform for positioning said platform relative to the top edges of the spools in the lower row, guide means on the upper side of the platform for aligning the spool flanges of a row of spools on the platform, means for clamping the top row of spools together as a unit, and means for anchoring the unit to the base support.

11. Apparatus for loading spool-shaped articles in a container for shipment comprising, a floor for receiving a plurality of spools in a row, a frame including a side member extending the length of each side of a row of spools and supported by the spools, said frame having means for positively engaging each spool axle to retain all the spools in fixed spaced relation, and means for anchoring the spool retaining means to the floor.

12. Apparatus for loading spool-shaped articles in a container for shipment comprising, a floor for receiving a plurality of spools in a row, a rigid member extending the length of each side

of a row of spools and having means for engaging the axle of each spool head whereby all the spools are retained in fixed spaced relation, and means for clamping the member rigidly to the spool heads to prevent relative rotational movement thereof.

13. Apparatus for loading spool-shaped articles in a container for shipment comprising, a floor for receiving a plurality of spools in a row, a member extending the length of each side of a row of spools and having spaced apertures for receiving the axles of each spool, and means for clamping the member rigidly to the spool heads to provide a rigid unit, and means for anchoring the spool head clamping members to the floor.

14. Apparatus for loading and stacking heavy spool-shaped articles on a floor comprising in combination with upper and lower rows of spools, a platform resting on the lower row and supporting the upper row of spools, means for anchoring the platform directly to the floor and means for anchoring the spools of the upper row directly to the floor.

15. Apparatus for loading and stacking heavy spool-shaped articles on a floor comprising in combination with upper and lower rows of spools, a platform resting on the lower row and supporting the upper row of spools, means for anchoring the top row of spools and the platform together as a unit, and means for anchoring the unit to the floor.

16. Apparatus for loading and stacking heavy spool-shaped articles on a floor comprising in combination with upper and lower rows of spools, a platform resting on the lower row and supporting the upper row of spools, means for clamping the individual spools of each row in rigid spaced relation as a unit, and means including a tensioning device for anchoring each unit to the floor.

17. Apparatus for loading and stacking heavy spool-shaped articles on a floor comprising in combination with upper and lower rows of spools, a platform resting on the lower row and supporting the upper row of spools, and means for anchoring the spools of the upper row on the platform and directly to the floor.

18. Apparatus for stacking and loading heavy spool-shaped articles comprising in combination, a floor for receiving a row of spools, each spool having end head flanges and protruding axle members, a frame for clamping all the spools together as a unit including a pair of individual side members arranged to engage the individual axle members at the end of each spool, and means for rigidly clamping the side members against the spool end flanges.

19. Apparatus for stacking and loading heavy spool-shaped articles comprising in combination, a floor for receiving a row of spools, each spool having end head flanges and protruding axle members, a frame for clamping all the spools together as a unit including a pair of individual side members arranged to engage the individual axle members at the end of each spool, means for rigidly clamping the side members against the spool end flanges and means located near the end of each side member for anchoring the side members to the floor.

20. The method of stacking and loading spool-shaped articles in a plurality of rows which consists in placing a plurality of said articles in a row on a base support, placing a platform on the upper edges of the articles in the lower row, placing a row of articles on said platform, se-

curing the articles in the second row together as a unit, and then anchoring the second row unit to the base support.

21. The method of stacking and loading spool-shaped articles which consists in placing a plurality of such articles in an aligned row on a base support, securing the individual articles of the row to each other to form a rigid unit, placing a platform on the upper edges of the articles in the lower row, placing a plurality of articles in an aligned row on said platform with the spool flanges in alignment with the spool flanges of the lower row, then anchoring the individual articles in said second row to form a unit, and then anchoring the unit to the base support.

22. The method of stacking and loading spool-shaped articles which consists in placing a plurality of such articles in an aligned row on a base support, securing the individual articles of the row to each other to form a rigid unit, placing a platform on the upper edges of the articles in the lower row, placing a plurality of articles in an aligned row on said platform to form a unit, securing the upper row of articles together as a unit, and then anchoring both the platform and the row unit of articles comprising the unit on the platform, to the base support.

23. The method of stacking and loading spool-shaped articles which consists in placing a plurality of such articles in an aligned row on a base support, securing the individual articles to each other to form a rigid unit, bracing the unit against endwise and lateral movement relative to the support, placing a platform on the upper edges of the articles in the lower row, placing a plurality of articles in an aligned row on said platform and securing the same as a unit, securing the platform relative to the upper and lower rows, and then anchoring the row unit of articles in said second row unit to the base support.

24. The method of stacking and loading spool-shaped articles which consists in placing a plurality of such articles in an aligned row on a base support, clamping the individual articles of the row to each other to form a rigid unit, superimposing a second row of articles clamped to each other to form a rigid unit on the first row so that the axes of the articles in each row shall be in vertical alignment, and then anchoring each row unit to the base support.

25. The method of stacking and securing for transportation on a car or truck body heavy flanged spools of thread such as rayon tire cord and the like and which spools have axial spindles projecting from opposite ends thereof, consisting in first disposing spools in superimposed substantially horizontally aligned rows, then rigidly connecting the projecting spindles of the spools of each row to one another to thereby hold spools of each row together as a unit, bracing the spools against lateral shifting movement and anchoring the rows of spools so connected and braced to the car or truck body.

26. The method of stacking and securing for

transportation on a car or truck body heavy flanged spools of thread such as rayon tire cord and the like, which consists in disposing a row of spools on the floor of a car or truck body with the flanges of the spools resting on the floor, disposing another row of spools in superimposed relation with respect to the lower row of spools but separated from said lower row to positively maintain the upper and lower rows of spools out of contact with one another, rigidly connecting the projecting spindles of the spools of each row to one another to thereby hold the spools of each row together as a unit, bracing the spools against lateral shifting movement, and anchoring the rows of spools so connected and braced to the car or truck body.

27. In apparatus for stacking and securing for transportation on a car or truck body heavy flanged spools of thread such as rayon tire cord and the like and which spools are disposed in superimposed rows and have axial spindles projecting from opposite ends thereof, rigid means extending longitudinally of the rows of spools in engagement with said spindles to connect and lock the spools of each row together as a unit, and means anchoring the rows of spools so connected to the floor of the truck or car body with the weight of the spools imposed on said floor.

28. Apparatus for stacking and securing for transportation on a car or truck body heavy flanged spools of strand material such as rayon tire cord and the like and which spools are disposed in superimposed rows and have axial spindles projecting from opposite ends thereof, comprising rigid members extending longitudinally of the rows of spools in engagement with said spindles to connect and lock the spools of each row together as a unit, means maintaining the rows of spools out of contact with one another, and means connecting said rigid members to the floor of the truck or car body with the flanges of the lower row of spools resting on said floor and taking part of the weight of the upper row.

29. Apparatus for stacking and securing for transportation on a car or truck body heavy flanged spools of strand material such as rayon tire cord and the like and which spools are arranged in superimposed rows and have axial spindles projecting from opposite ends thereof, comprising rigid members extending longitudinally of said rows of spools and having means engaging over said spindles to lock the spools together in rows, a partition overlying and resting on the flanges of the lower row of spools and having the flanges of the upper row resting thereon to positively maintain the spools of one row out of contact with the spools of the other row, and means connecting said rigid members to the floor of the truck or car body with the flanges of the lower row of spools resting on the floor and taking part of the weight of the upper row.

HENRY B. KOONCE.
